CLAIM

The ornamental design for a transceiver module, as shown and described.

DESCRIPTION

FIG. 1 is a front, side perspective view of a transceiver module, showing my new design;

FIG. 2 is a front elevational view thereof;

FIG. 3 is a rear elevational view thereof;

FIG. 4 is a side elevational view thereof;

FIG. 5 is a side elevational view thereof, opposite that shown in FIG. 4;

FIG. 6 is a top plan view thereof;

FIG. 7 is a bottom plan view thereof; and,

FIG. 8 is a perspective view of the transceiver module of FIG. 1 shown in its intended use.

The broken lines shown herein are for illustrative purposes only and form no part of the claimed design.

1 Claim, 6 Drawing SheetsFIG. 2.

FIG. 3.

FIG. 4.

FIG. 5.

FIG. 6.

FIG. 7.
